UNITED STATES PATENT OFFICE.

LESLIE N. CRICHTON, OF WILKINSBURG, PENNSYLVANIA, ASSIGNOR TO WESTINGHOUSE ELECTRIC & MANUFACTURING COMPANY, A CORPORATION OF PENNSYLVANIA.

ELECTRICAL PROTECTIVE RELAY.

Application filed May 26, 1923. Serial No. 641,701.

My invention relates to electrical protective devices and particularly to protective relays.

One object of my invention is to provide a protective relay for sectionalizing a portion of an electrical system which becomes faulty.

Another object of my invention is to provide relays for the above purpose having such characteristics that, in a system divided into 10 a plurality of sections by substations and circuit-interrupting devices, only those relays which are nearest to the faulty section and control the circuit interrupters, including the faulty section, shall operate to isolate that 15 section.

A further object of my invention is to provide a relay that shall automatically vary the time element of its operation in accordance with its distance from the location of 20 the fault.

A further object of my invention is to provide a relay of the above character embodying means whereby the relay may be continuously energized from the circuit at normal 25 voltage and yet be sensitive at relatively small values of voltage.

A further object of my invention is to provide a relay embodying control elements that are so arranged as to permit substantially instantaneous operation of the relay when the voltage in that portion of the circuit at which the relay is disposed decreases to substantially zero.

A still further object of my invention is to provide a relay that shall be positive in operation and rugged in construction, notwithstanding its sensitivity.

Figure 1 of the accompanying drawings is 40 a diagrammatic view of a portion of a network illustrating the elemental connections to the system, of the relay embodying my invention.

Fig. 2 is a schematic view of the relay embodying my invention and illustrates the relative arrangement of the different parts of the relay and the connections thereof to the circuit.

Fig. 3 is a perspective view of the relays constructed in accordance with the principles 50 of my invention.

Fig. 4 is a view, partially in section and partially in elevation, of the voltage coil or restraining element.

Fig. 5 is a diagrammatic view of a ring distribution system, and

55

Fig. 6 is a diagrammatic view illustrating schematically a modification of the relay embodying my invention as constructed to provide a directional feature.

In practicing my invention, I provide a 60 current element of the induction type similar to the induction type overload relays at present employed in protecting electrical systems. The disc is arranged to operate through a spring upon an arm on a pivoted lever to 65 cause the lever to close an auxiliary control circuit. A voltage element comprising a voltage coil and movable core member is arranged to act upon a second arm connected to the pivoted lever to counteract the force 70 of the current element under predetermined normal conditions.

The lever is so balanced that, when the voltage coil is deenergized, very slight movement of the disc will actuate the lever to close 75 the auxiliary control circuit instantaneously. If the voltage coil is energized, however, the current element will continue to store energy in the spring disposed between the disc and the first moment arm connected to the lever 80 until the force developed in the spring overcomes the torque of the voltage restraining element and the lever is actuated to close the contacts to close the auxiliary circuit.

The angular velocity of the disc is proportional to the magnitude of the short-circuit current and its motion tends to close the contacts, which operation is restrained however, by the voltage element. The voltage coil acts on the core member which consists of a 85

small steel element so proportioned that it saturates at a very low voltage on the coil and the pull upon the core member therefore varies directly as the voltage on the coil. The time of operation of the relay, that is, the 90

time of closing of the auxiliary circuit, varies, therefore, inversely in accordance with the current and directly in accordance with the voltage. Since the voltage is lowest near the fault, the time of operation depends upon the 95

distance between the relay and the fault, and, therefore, the relays nearest the fault will operate first and those farther away will require a longer interval of time to close. Under such circumstances, the operation of 100 the relays nearest the fault will isolate the 105

faulty portion of the system and the other relays will then reset themselves.

In Fig. 1, I have illustrated the manner of connecting the winding of the relay to a portion of the circuit between the two substations 10 and 11. A voltage restrained relay 12 is provided with a current winding 13 and a voltage winding 14 that are differentially effective in controlling the closing of the contactive device 15 that controls an external auxiliary circuit 16 containing the trip coil of an associated interrupter.

Upon reference to Figs. 2 and 3 in which the parts of the relay are shown in greater detail, it may be seen that the relay comprises the current element 13, the voltage element 14, the contactive device 15 and a pivoted lever 17 for controlling the operation of the contactive device.

The current element 13 comprises a movable induction disc 20, an actuating magnetizable core member 21 which is energized from the circuit through a current transformer 22. A damping magnet 23 is provided to restrain somewhat the action of the induction disc and tends to so control the disc as to cause its angular velocity to be substantially proportional to the value of the current energizing the magnetizable member 21. The winding of the current element is provided with a plurality of taps whereby the operating value of the element may be adjusted for different current values. These taps are illustrated in Fig. 3 at the points 24.

The voltage element 14 comprises a coil 26 which is energized from the circuit through a potential transformer 27. A plurality of resistors 28 are provided with means whereby one or more of the resistors may be inserted in circuit with the voltage coil. The voltage element comprises further a movable core member 30 of magnetic material, preferably steel, having a low magnetic retention and adapted to become saturated when relatively low values of voltage are impressed upon the coil.

The core member 30 is pivoted at a point 31 to the lever arm 17 and the portion of the lever between the point 31 and the pivots 32 may be regarded as a moment arm of the torque developed by the voltage coil for restraining the lever 17 from effecting engagement of the contact members 15.

The lever 17 is also provided with a depending arm 33 which constitutes the moment arm upon which the force of the current element 13 is impressed through a spring 34 in such direction as to turn the lever 17 to effect engagement of the contact members 15. It will be seen, upon referring to Fig. 2, that the current element tends to move the arm 33 toward the right-hand side to lower the left-hand end of the lever 17 to effect engagement of the contact members 15, whereas the voltage element pulls downwardly upon the right-

hand end of the lever 17 to restrain the action of the current element and thereby delay or preclude the effective engagement of the contact members 15.

In Fig. 3 in which the current element is illustrated in greater detail, a set of gears 35 is interposed between the spring element 34 and the arm 33 and disc 20. This construction permits of greater extent of movement of the current element before the spring 34 is stressed to a great extent.

In the same figure, it will be seen that the iron case 38 constituting the magnetic circuit of the voltage element is provided with a plurality of flanges or ribs 39 to assist in radiating the heat that is developed by the voltage coil. Inasmuch as the voltage coil must be sensitive and operative when energized even to a relatively low degree, such, for example, as 4% or 5% of normal voltage, it is necessary to provide some means for dissipating the heat that is developed by the coil when energized by the normal operating voltage.

The construction of the voltage element may be more readily comprehended upon reference to Fig. 4 in which the voltage element 14 is illustrated as comprising, in addition to the core member 30 and the surrounding coil 26, the cylindrical casing or box 38 of cast iron that constitutes part of the magnet circuit for the coil. The core member 30 that is controlled by the voltage coil is supported from a bearing frame 40 in which is mounted a jewel screw 41 that is disposed to receive a pin 42 that is secured to the end of the lever arm 17. The coil 26, when energized, pulls down upon the core member 30 and, through the bearing, the jewel screw pulls down upon the lever 17. The pin and the jewel screw are adjusted to prevent the bearing frame from slipping off the pin 42.

The core member 30 is provided with an enlarged portion at its lower end to decrease the reluctance at that point. A brass pin and washer 44 are secured to the enlarged portion and cooperate with a stop member 43, that is disposed in the base of the casing 39, to limit the downward movement of the core member 30 which is shown in its lowest or attracted position.

The washer serves to preclude surface-to-surface engagement of the enlarged portion of the core member and the stop 43, and the pin serves to maintain the core member in vertical alignment to preclude frictional engagement between the core member and the inner surface of the coil. It will be noted that the travel of the core member is small.

Normally, the voltage element is calibrated to produce a torque that will just exceed the normal torque of the current element and the pivoted lever is maintained in its ineffective position to permit the contact members to remain open. When the voltage element is entirely deenergized, it will be seen that very

little force, hence very little movement, of the current element is necessary to effect the engagement of the contact members 15 through the pivoted lever 17 by reason of the relatively 5 long moment arm.

Between the conditions of complete deenergization of the voltage coil and normal energization thereof, the time interval of operation of the relay varies between instantaneous 10 operation or zero time element to non-operation or infinite time element. Since the voltage that will be impressed on the voltage coil depends upon the distance of the relay from the fault, the time element of operation 15 of the relay will also depend upon its distance. The closer the relay is to the fault, the lower will be the voltage on the element 14, and, consequently, the shorter will be the time element of operation of the relay.

20 In Fig. 5 is illustrated a closed or ring system of distribution in connection with which it is possible to readily explain the application of my relay. If a fault should occur at the point A, the relay associated with 25 the circuit-interrupting device 50, being the closest to the location of the fault, would operate in less time than any of the relays associated with the other circuit-interrupting devices and the faulty section would be disconnected, and isolated by the opening of 30 the circuit-interrupting device 50 before any of the other relays operated to effect the opening of the associated circuit interrupters. For this application, since energy can flow in 35 only one direction, the single element which I have illustrated in Figs. 2 and 3 will suffice.

For portions of the circuit within the ring, however, it is necessary to provide a relay that 40 will take into consideration not only the distance of the particular relay from the location of the faulty condition but also the direction in which energy is flowing toward the faulty condition. If, for example, the portion 45 of the system between the substations 54 and 55 be considered, it will be seen that, upon the occurrence of a fault in that portion of the system at the point B, energy will flow to the fault through the substation 54 and also around through the right-hand portion of the 50 ring through the substation 55. Since the substation 54 is provided with two circuit-interrupting devices 56 and 57 and the substation 55 is provided with two circuit-interrupting devices 58 and 59, it is essential 55 that some selective means be provided to control the operation of the proper circuit interrupters in accordance with the direction of energy flow to the fault. For applications to systems of this type, I provide a relay structure, as illustrated schematically in Fig. 6, 60 which embodies, in addition to the voltage-restrained element 12 previously described, a directional element 60 that is similar to that employed in reverse power relays, such as illustrated and described in Patent 65

No. 1,365,228, issued Jan. 11, 1921, to B. H. Smith.

The contacts 61 of the directional element are arranged to close a circuit in series with the contacts 15 of the voltage-restrained element for tripping the circuit-interrupter 62. The directional elements of the relays associated with the interrupters 57 and 58 are arranged to close their contact members only when energy flows from the substations into 75 the section connecting the stations. Thus, upon the occurrence of a fault in the sections between the stations 54 and 55, the voltage-restrained elements of the relays associated with both of the interrupters 56 and 57 would 80 operate to close their contact members at the same time after an interval depending upon the distance of the station 54 from the fault.

Similarly, the voltage-restrained elements 85 associated with the circuit interrupters 58 and 59 would operate to close their respective contact members at the same time after an interval depending upon the distance of the fault from the station 55.

Although the voltage-restrained relays 90 associated with the respective circuit interrupters in the same station close their contacts at the same time, both interrupters in each station will not be operated since the directional elements of the relays are so arranged as to close only when energy flows 95 from the stations 54 and 55 to the fault. Under such conditions, only the relays associated with the interrupters 57 and 58 will become effective to trip the latter and they will 100 open to isolate the faulty section between the stations 54 and 55, leaving the stations 54 and 55 connected to the system.

My invention thus comprehends a relay 105 device that shall operate to close its contact members after an interval of time that is proportional to its distance from the location of a fault when a faulty condition occurs in the system. By such means, I am able to isolate 110 only the faulty section and to permit the remainder of the system to continue to transmit energy.

My invention is not limited to the specific arrangements that I have illustrated, but may 115 be variously modified without departing from the spirit and scope thereof, as set forth in the appended claims.

I claim as my invention:

1. In an electrical system, a protective relay embodying two operating coils energized 120 from the circuit and means for counterbalancing their effects comprising a pivoted lever contact, an induction disc subject to the influence of one coil for controlling the lever in one direction and a movable restraining member subject to the influence of the other coil for opposing the operation of the lever.

2. A protective relay comprising a pivoted lever, a contactive device controlled thereby, 125 an induction meter element and a spring con-

- trolled thereby for actuating the lever arm in one direction, means for damping the effect of the induction element upon the spring, and electromagnetic means for producing a relatively small torque acting against the force of the induction element upon the lever arm to retard the operation thereof.
3. A protective relay comprising a pivoted lever, a contactive device controlled thereby, an induction meter element, an arm depending from the lever adjacent to the pivot, a spring controlled by the induction element and operative to exert a gradually increasing torque upon the lever through the depending arm, and a counteracting element comprising a coil and a movable core member subject to the influence of the coil for determining the time elapsing before the lever is actuated.
- 20 4. A protective relay comprising a pivoted lever, a contactive device controlled thereby, an induction meter element, means constituting two moment arms for controlling the lever, energy-storing means disposed between the induction element and one arm tending to exert a varying torque on the lever, and means controlling the other arm tending to restrain operation of the contact member until the torque on said lever exceeds a certain value.
- 25 5. In an electric circuit, a protective relay embodying a pivoted lever, a contactive device controlled thereby, two members constituting moment arms of the lever, a current-controlled element connected to one moment arm to control the movement of the lever, a voltage-controlled restraining element connected to the other arm and operative to prevent actuation of the lever under certain conditions and means for energizing 30 said elements in accordance with the current and voltage of the circuit, respectively.
- 40 6. In an electric circuit, a protective relay embodying a pivoted lever, a contactive device thereon, two members constituting moment arms for the lever, a current element, a spring controlled thereby for controlling one moment arm, a voltage restraining element on the other arm acting counter to the current element and means for energizing said elements in accordance with the current and voltage of the circuit, respectively.
- 50 7. In an electrical system, the combination with a current transformer and a potential transformer, of an induction type current element energized from the current transformer, a solenoid energized from the potential transformer, a pivoted member, a contactive device controlled thereby, a spiral spring controlled by the induction current element for gradually impressing an actuating force on the lever tending to operate the contactive device and means subject to the control of the solenoid for varying the time of operation of the lever; the pivoted lever, the induction element and the solenoid being 55 so balanced that slight movement of the induction element will operate the contactive device when the solenoid is not energized.
8. A protective relay energized from the circuit comprising a contactive device, an induction element energized in accordance with the current in the circuit, a spiral spring between said element and said contactive device, and a voltage element energized in accordance with the circuit voltage and disposed to restrain the operation of the contactive device until the tension in said spring exceeds a certain value.
- 70 9. In combination with an electric circuit having a definite normal voltage, a relay comprising contact members, means including a pivoted induction-meter element for exerting a gradually increasing torque tending to close said contact members when the current in said circuit exceeds a predetermined value 75 and restraining means energized in accordance with the voltage of said circuit for preventing the closure thereof until a sufficient torque is exerted, said restraining means comprising a magnetizable core member that is 80 saturated at a relatively low voltage and electromagnetic means tending to hold the same against a stationary stop.
- In testimony whereof, I have hereunto subscribed my name this 19th day of May, 1923.
- LESLIE N. CRICHTON.
